UNITED STATES PATENT OFFICE.

NELSON NYBERG, OF GLOBE, ARIZONA.

STAND.

1,111,607.

Specification of Letters Patent. Patented Sept. 22, 1914.

Application filed October 15, 1913. Serial No. 795,261.

To all whom it may concern:

Be it known that I, NELSON NYBERG, a citizen of the United States, and a resident of Globe, in the county of Gila and State 5 of Arizona, have invented a new and Improved Stand, of which the following is a full, clear, and exact description.

My invention relates to stands comprising a standard and a support to constitute a 10 book rest, music holder, or a table for light service, and the invention relates particularly to a stand of the indicated character in which the support is mounted to turn about the standard, and having a swivel 15 connection with the latter to assume various angles with respect to the horizontal, or to be partially inverted for reading in a reclining position, or to be turned completely over if desired.

20 The invention resides in the novel features of construction and combinations of parts as hereinabove particularly described.

Reference is to be had to the accompanying drawings forming a part of this specification, in which similar characters of reference indicate corresponding parts in all the views.

Figure 1 is a front elevation of a stand embodying my invention; Fig. 2 is a partial 30 end view thereof; Fig. 3 is an enlarged front view of the support or book rest detached from the standard; Fig. 4 is a longitudinal section on the line 4—4 of Fig. 2; Fig. 5 is a cross section approximately on the line 5—5 of Fig. 3; and Figs. 6 to 9 are diagrammatic views illustrating various uses of the stand.

In constructing a stand in accordance with 40 my invention, a standard or upright 10 is provided, having a suitable base 11, and mounted on the same is a support adapted to constitute a book rest, music holder, or table. The support 12 is mounted on the standard 10, to turn thereon, the standard 45 being provided with a set collar 13, to be adjusted at various heights, and there being a bracket 13 of U-shape, the arms of which slip onto the standard 10, above the support.

As here shown, the support 12 has a bolt 50 hole 12^a in a side thereof, to receive the bolt 15 having a wing nut 16 or the like, the arrangement providing a swivel connection for the support 12 relatively to the bracket 14. The slatted or other bottom 12^b 55 of the support 12 is adapted to constitute a rest for a book A, and to hold the latter in

the open position a clamp rod 17 is provided, adapted to be received in one of a vertical series of holes 12^c, the clamp rod being provided with an eye 17^a or other 60 finger hold at the front for the convenient insertion and removal of said rod. Overhanging the bottom 12^b are rocker fingers or arms 18, 18^a, to hold the leaves of the book A open. The fingers 18, 18^a, are fulcrumed as at 19 on the support 12, preferably between ears 20 formed on clips 23, the one clip being on the outer end of the support 12, and the other on a partition 12^d near the swiveled end of the holder. The 70 short arms of the fingers 18, 18^a, are connected by links 21 with levers 22, 22^a, which are actuated in a manner hereinafter described, said levers being guided in keepers 24, formed by turning up the lower ends 75 of the clips 23. The said clips at the inner side are formed with feet 25, to which are secured at one end, retractile springs 26, the opposite ends of which springs are connected with the respective fingers 18, 18^a, to 80 normally hold the said fingers in the lowered position over the book A, or the like.

Additional guides are provided for the levers 22 in the form of clips 27, 27^a. One of the levers, as 22, has an operating arm 28, 85 having an offset finger piece 29 at the upper end for the operation of the lever. On the arm 28 is a rack 30, meshing with which is a sector 31 on one arm of a bell crank lever 32, and a connecting rod 33 extends from 90 said bell crank lever to a crank arm 34 on a shaft 35 mounted to turn in the holder 12 at the opposite end from the bell crank lever. On the shaft 35 at the end opposite the arm 34, is a rocker arm 36 formed with a toothed 95 sector 37, which meshes with a rack 38 similar to the rack 30 and secured to the adjacent lever 22^a. It will be obvious that pressure on the finger piece 29 will rock the lever 22, and through the adjacent link 21 will raise 100 the finger 18, and at the same time through the connecting rod 33 and the described connections the lever 22^a will be simultaneously rocked and raise the finger 18^a.

The fingers 18, 18^a permit the leaves of 105 the book A to be turned from beneath one finger and passed under the other. The swivel connection permits of the holder 12 being adjusted to the position shown in Fig. 6, to constitute a music holder, or a book rest for reading in a standing position, or the said holder, while adjusted approxi-

mately to the inclination shown in Fig. 6 may be lowered to the position shown in Fig. 7, for holding a book to be read by a person seated on a chair, as B. In Fig. 8 5 the holder 12 is shown partially inverted, so that a book may be read by a person reclining on a bed as C; in this position the fingers 18, 18^a, support the book and prevent it from closing. In Fig. 10 the holder is 10 shown as arranged on the standard 12, to be used as a table for light service.

It will be clear from the foregoing that the device may be very readily adjusted for its various purposes, and that the rocking of 15 the arms 18, 18^a, may be very conveniently effected.

Having thus described my invention, I claim as new and desire to secure by Letters Patent:

20 1. In a stand of the character described, a standard, a holder adapted to receive a book or other article to be held, means for swiveling the support on the standard, and means for holding a book on the support facing either upwardly or inverted, a clamp rod 25 for clamping a book or a piece of music at the center, fingers mounted at their outer ends to be rocked and disposed toward each other, springs normally tending to hold the 30 fingers in the lowered position to overlie the leaves of the book, levers linked to the said fingers, guide keepers for the levers, racks on the levers, toothed sectors meshing with the racks, rocker elements in rigid relation 35 to the sectors, and a connecting rod uniting said rocker elements.

2. In a stand of the character described, a holder to receive a book or the like, means for clamping the book, said means including fingers, clips secured to spaced members 40

of the holder, the clips having ears on which the fingers are fulcrumed, the clips at the inside each being formed with a foot, springs connected with the feet and with the respective fingers at the interior of the holder, the 45 clips furthermore being upturned at the outer sides thereof constituting guides, levers fulcrumed to the holder and movable in said guides, links connecting the levers with the fingers, and means for operating 50 the levers in unison.

3. In a stand of the character described, a holder to receive a book or other article, fingers overlying the holder at their inner ends, the fingers being fulcrumed intermediate their ends, springs normally acting to hold the fingers in the lowered position, levers for rocking the fingers, links connecting the levers with the fingers, guide keepers on the holder near the outer ends of the 60 levers, and additional guide keepers on the holder inward from the first guide keepers.

4. In a stand of the character described, a holder to receive a book or the like, means for mounting said holder, fingers fulcrumed 65 at their outer ends on the holder and extending toward each other, levers operatively connected with the fingers, said levers being formed with racks and one of the levers having a finger piece, toothed sectors engaging the racks and mounted to rock, and connections between the respective sectors.

In testimony whereof I have signed my name to this specification in the presence of two subscribing witnesses.

NELSON NYBERG.
